UNITED STATES PATENT OFFICE.

MAYER SLOTKIN, OF NEW YORK, N. Y., ASSIGNOR OF ONE-HALF TO
JULIUS PRAGLIN, OF NEW YORK, N. Y.

FOOT-POWER MECHANISM.

SPECIFICATION forming part of Letters Patent No. 762,004, dated June 7, 1904.

Application filed May 29, 1903. Serial No. 159,243. (No model.)

To all whom it may concern:

Be it known that I, MAYER SLOTKIN, a citizen of the United States, residing in New York, borough of Manhattan, in the State of New York, have invented certain new and useful Improvements in Foot-Power Mechanisms, of which the following is a specification.

This invention relates to certain improvements in foot-power mechanisms by which power may be conveniently and effectively imparted to sewing-machines, drills, lathes, and other light machinery by the foot of the user when the user is either sitting or standing, the movement being not in the nature of that compelled by an oscillating treadle, but being a forwardly-directed "kick," by which means the foot-muscles are less fatigued than when motion is given by the ankle; and for this purpose the invention consists of a foot-power mechanism which comprises upright standards, a fly-wheel the shaft of which is supported in bearings of said standards, a clutch on the shaft of the fly-wheel, a pinion on said clutch, a toothed segment meshing with said pinion, and a lever attached to the segment and provided with a foot-rest at its lower end, the upper end of the segment being provided with a lateral stop for limiting the forward or return movement of the segment and foot-lever by contact with the casing of the clutch.

The invention consists, further, of a pivoted and spring-actuated knee-brake which is applied to the upper end of the standards for permitting the quick stoppage of the foot-power by the attendant whenever required.

In the accompanying drawings, Figure 1 represents a perspective view of my improved foot-power mechanism. Fig. 2 is a plan view of the same; and Fig. 3 is a vertical section on line 3 3, Fig. 2, through the clutch, on a larger scale.

Similar letters of reference indicate corresponding parts.

Referring to the drawings, A represents the base-plate of my improved foot-power mechanism. On the base-plate A are supported two parallel standards B B, which are preferably cast integral with the base-plate A and which carry at their upper ends in back-

wardly-ending brackets *a* bearings *a* for the shaft *f* of the fly-wheel F. These bearings are preferably located at some distance below the upper ends of the standards B. At the upper forwardly-extending end of one of the standards B is arranged a bearing *d*, which receives the pivot of a foot-lever L, said pivot being inserted into the bearing and retained in the same in any suitable manner, so as to form the fulcrum on which the foot-lever L swings. To the shaft of the fly-wheel is applied a clutch C of any improved construction, which clutch is so constructed that it will impart motion to the fly-wheel shaft when moved in one direction, but clear the same when it is moved in the opposite direction. This clutch may be, for example, of the construction shown in my Patent No. 715,164, dated December 2, 1902, or it may be of any approved construction. In the machine shown in the drawings it consists of a ratchet-wheel *h*², keyed to the shaft *f*, a housing *h*, connected with the pinion *e* and inclosing the ratchet-wheel *h*², and a pawl *h'*, connected with the housing *h* and actuated into engagement with the ratchet-wheel by a suitable spring *h*³. When the foot-rest *r* is moved rearwardly, the housing and ratchet are moved thereby in the direction indicated by the arrow in Fig. 3, whereby the ratchet engages the ratchet-wheel, and the shaft *f* is turned. Upon the return motion of the treadle the housing *h* and pawl are moved in the return direction, whereby the ratchet passes over the teeth of the ratchet-wheel. On the casing of the clutch is arranged a pinion *e*, which is placed in mesh with a toothed segment E, which is rigidly attached, by means of fastening-bolts *e'*, to the upper curved portion of the foot-lever L, as shown in Fig. 1. The lower end of the foot-lever is curved in backward direction and then in forward direction and provided at its forward end with a foot-rest *r*, which is ribbed in a suitable manner, so as to give the desired support to the foot. To the upper end of the toothed segment E at its point of connection with the upper end of the curved foot-lever L is arranged a laterally-projecting stop-pin *p*, which is of sufficient length so as to abut against the

casing of the clutch, which thereby forms a stop when the rearward motion of the foot-lever under the influence of the momentum of the fly-wheel takes place, said stop-pin arresting the motion of the foot-lever, and thereby limiting the rearward movement of the treadle. Mutilation of the teeth of the pinion by abutment of the same against the outer end of the lever, which heretofore frequently occurred, 10 is thus obviated. The stop-pin and clutch-casing provide a means independent of the pinion for arresting the segment. The forward movement of the treadle is limited by the lower end of the segment, which is arranged at an angle to the toothed portion, as 15 shown at ϵ^2 , Fig. 1. This angular portion forms a stop device by which the forward motion of the lever L is limited while the projecting stop-pin p forms a stop device for the 20 foot-lever during the backward motion of the same. It thereby keeps the treadle always under control of the operator and prevents the slipping away of the same during the motion under the momentum of the fly-wheel, as 25 has been the case heretofore.

To the upper end of the standard B, which carries the fulcrum of the foot-lever L, is fulcrumed a forwardly-extending brake-arm g , which is acted upon by a suitable spring s , 30 said arm being provided with a rear extension g' , which abuts against a pin g^2 on the standard B, as shown clearly in Fig. 2. The forward end of the fulcrumed and spring-actuated brake-arm g carries a brake-shoe of 35 rubber or other suitable material that is attached thereto, so as to project toward the rim of the fly-wheel. The brake-arm is intended to be operated by the knee of the operator whenever the foot-power is to be 40 stopped. The pressure on the enlarged end of the brake-arm will cause the shoe to impinge on the rim of the fly-wheel and stop the motion of the same, the foot-pressure on the treadle being at the same time discontinued. By the 45 brake action thus applied the momentum of the fly-wheel is quickly stopped and the foot-power better adapted for interrupting the motion of the sewing-machine or other light machine driven by foot-power than heretofore. The stop-pin g^2 is so located as to arrest the brake, 50 which is of such length that it would otherwise swing into the way of the operator before it reaches that point. The stop-pin g^2 is so located as to arrest the brake 55 in a vertical plane between the wheel and the treadle r , as shown in Fig. 2, so that the brake, which otherwise would be free to turn upon its pivot into the plane of the treadle, and thereby by interference with the operator 60 interfere with the treadle, is positively arrested before it arrives at such interfering position.

The operation of my improved foot-power mechanism is as follows: When the foot is 65 placed on the foot-rest r and moved in for-

ward direction, oscillating motion is imparted to the foot-lever L, so that the toothed segment E meshes with the pinion e of the clutch C and imparts rotary motion to the clutch and by the same to the shaft of the fly-wheel, 70 so that the latter is turned in the direction of the arrow shown in Fig. 1. By gravity the foot-lever is returned into forward position and arrested by the contact of its stop-pin with the casing of the clutch. When the foot-lever and its treadle are in returned position, another impulse or kick is imparted by the foot to the same. By repeating these kicks a continuous rotary motion is imparted to the fly-wheel and from the same by suitable 75 belt and pulley transmission to the spindles or shafts of the sewing-machine, lathes, drills, buffing, or other light machinery to be driven by foot-power, said machine being supported on a table above the foot-power mechanism. 80 The foot-lever and clutch-mechanism turn the fly-wheel always in one and the same direction as soon as motion is imparted to the foot-lever, the fly-wheel continuing its rotary motion and imparting the return motion to the foot-lever and treadle. Whenever the foot-power is to be arrested, the brake is called into action by the pressure of the knee on the same, the 85 brake-shoe being instantly removed as soon as the pressure is relaxed. 90

My improved foot-power mechanism is of simple construction and can be operated either with one or two foot-levers, the forward motion of the foot on the foot-rest starting the machine, which is kept continuously in motion by repeated kicks without the use of hands, the fly-wheel always turning in the same direction. By the pendulum motion of the foot-lever or foot-levers the whole strength of the limbs can be applied, so that there is 105 less fatigue than with the ankle movement required for operating treadles. By the 100 clutches great power and momentum is imparted to the fly-wheel with each motion of the foot-lever, so that the fly-wheel will run 110 smoothly and speedily for some time before the next motion of the foot-lever or kick is necessary. By increasing the number of kicks the speed and power of the machine are increased. Thus a very effective foot-power 115 mechanism for all kinds of light machinery is obtained for shops in which no steam-power is available or in which it is not desirable to apply expensive transmission-power to all the 120 smaller machines. 120

Having thus described my invention, I claim as new and desire to secure by Letters Patent—

1. A foot-power mechanism, consisting of upright standards, a fly-wheel, the shaft of which is supported in bearings of said standards, a clutch applied to the shaft of said fly-wheel, a pinion on said clutch, a foot-lever fulcrumed to one of said standards and provided with a foot-rest at its lower end, a toothed segment attached to the upper end of 130

said foot-lever and adapted to mesh with the pinion on the clutch, and a laterally-extending stop-pin at the upper end of said segment, substantially as set forth.

5 2. In a foot-power mechanism, the combination, with upright standards, of a fly-wheel, the shaft of which is supported in bearings of said standards, a clutch applied to the shaft of said fly-wheel, a pinion on said clutch, a foot-lever fulcrumed to one said standards, a toothed segment pivoted to mesh with said pinion, means connecting said segment at its

lower end with the foot-lever, and a stop-pin connecting said foot-lever and segment at the upper end of the latter and projecting laterally therefrom into line with the clutch, substantially as set forth. 15

In testimony that I claim the foregoing as my invention I have signed my name in presence of two subscribing witnesses.

MAYER SLOTKIN.
